H. ROSENTHAL.

TRIMMING.

No. 17,189.

Patented Mar. 15, 1887.

UNITED STATES PATENT OFFICE.

HERMAN ROSENTHAL, OF NEW YORK, N. Y.

DESIGN FOR TRIMMING.

SPECIFICATION forming part of Design No. 17,189, dated March 15, 1887.

Application filed January 20, 1887. Serial No. 224,954. Term of patent 3½ years.

To all whom it may concern:

Be it known that I, HERMAN ROSENTHAL, a citizen of the United States, residing at New York, in the county and State of New York, have invented and produced a new and original Design for Trimmings, of which the following is a specification, reference being had to the accompanying drawing, forming part thereof.

10 The design relates to a trimming, and consists of a bar, circular loops projecting from one edge of the bar, and V-shaped loops projecting from the opposite edge of the bar, said circular and V-shaped loops being arranged directly opposite each other, so as to impart a novel and ornamental appearance to the trimming.

In the accompanying drawing the design is represented in front elevation.

20 A represents my trimming, which is ornamented by a bar, *a*, from one edge of which

project the loops *b*, which are circular, as shown. From the opposite edge of the bar *a* project loops *c*, which are V-shaped, as shown. The circular loops and the V-shaped loops are 25 arranged directly opposite each other.

What I claim as new, and desire to secure by Letters Patent, is—

The design for a trimming, consisting of the bar *a*, the circular loops *b*, projecting from one 30 edge of the bar, and the V-shaped loops *c*, projecting from the opposite edge of the bar, said circular and V-shaped loops being arranged directly opposite each other, substantially as shown and described.

In testimony whereof I have hereunto set my hand and seal in the presence of two subscribing witnesses.

HERMAN ROSENTHAL. [L. S.]
Witnesses:

W. HAUFF,
E. F. KASTENHUBER.
